UNITED STATES PATENT OFFICE.

CLARENCE NOEL CAHUSAC, OF JERSEY CITY, NEW JERSEY.

PHONOGRAPH-RECORD-FILING CABINET.

Application filed November 16, 1921. Serial No. 515,525.

To all whom it may concern:

Be it known that I, CLARENCE NOEL CAHUSAC, a citizen of the United States, and resident of Jersey City, in the county of Hudson and State of New Jersey, have invented certain new and useful Improvements in Phonograph-Record-Filing Cabinets, of which the following is a specification.

This invention is an improved filing cabinet for disk records such as are employed in apparatus for reproducing speech, music, or other sounds, and commonly known generically as phonographs.

The main object of my invention is to have the records so supported and mounted that they may be brought to view in succession and quite rapidly, to permit the selection of a particular record, and to facilitate the search for one, and any record when brought to view may be easily withdrawn for use. As a further object the record carriers are connected together in series in such a way that they may be superposed in two piles, the carriers being withdrawn in succession from the top of one pile and transferred to the top of the other, as they pass into and out of the exposed position. In this way the records are compactly stored in comparatively small space. The carriers are preferably in the form of envelopes which are flexibly connected together, the envelopes serving to protect and conceal the matrix surface grooves, while exposing the center or name-bearing portion, and preventing any escape or displacement of the record from the carrier except when the carrier is in the one exposed position.

A further object of my invention is to adapt the holders for different sized records, while at the same time holding any size of record in proper centralized position. Other objects of my invention and advantages of a preferred embodiment thereof will be apparent from or pointed out in connection with a detailed description of the illustrated construction.

In the accompanying drawings:

Fig. 1 is a perspective view of a construction embodying my invention, a portion of the casing being broken away,

Fig. 2 is a perspective view on a somewhat larger scale,

Fig. 3 is a section through the upper portion of the casing and on a somewhat larger

scale, said section being taken in the plane of the line 3—3 of Fig. 4,

Fig. 4 is a section on the line 4—4 of Fig. 3,

Fig. 5 is a sectional detail of a portion of the drum support, said section being taken on the line 5—5 of Fig. 6,

Fig. 6 is an end view of the parts shown in Fig. 5,

Fig. 7 is a plan view of a portion of the series of record carriers,

Fig. 8 is a section on the line 8—8 of Fig. 7,

Fig. 9 is a section on the line 9—9 of Fig. 7, but on an enlarged scale,

Figs. 10 and 11 are similar sections through a record carrier showing the guide for permitting the holding of different sized records, and

Fig. 12 is a view similar to Fig. 7, but showing a modified form of flexible connection between successive carriers.

In my improved construction each phonograph record or other flat disk-like member is removably mounted in a separate carrier 10, the several carriers being flexibly connected in series so that the connections in the strip or series may serve as reversible hinges and permit the carriers to be directly superposed and stacked in separate piles 11 and 12 upon opposite sides of a partition 14 in a casing 15. The casing may be a separate article of furniture and entirely independent of the phonograph, as indicated in Figs. 2, 3 and 4, or it may be incorporated in the same casing which carries or supports the operating mechanism of the phonograph.

As shown in Fig. 1, there are two casing sections 15^a, 15^b, each adapted to receive the record carriers and records, and these are spaced apart to support an intermediate section 13 within which the phonograph may be mounted.

Within the casing the space upon opposite sides of the partition is of a cross sectional area substantially equal to the size of each record carrier so that the stacks of carriers are held against any lateral or shifting movement, but sufficient free play is provided to permit the free lifting of the records from either stack and the delivery of them to the top of the other stack.

In the upper portion of the casing is a drum 16 over which the series of carriers 110

may pass from one pile to the other. This drum is polygonal in cross section, and each side is of a width approximately equal to the width of the envelope. I do not wish to be limited to any particular number of equal sides for the drum, but find that a triangular drum operates very efficiently. The drum is supported on a shaft or axle 17 journaled in opposite sides of the casing 18 at a point sufficiently close to the upper end or open top of the casing so that a portion of the drum extends above the plane of the upper edges of the side walls of the casing. The distance between the shaft 17 and the upper edge of the casing wall is sufficiently less than the minimum radius of the drum so that when a flat side of the drum is uppermost, the envelope thereon will lie in a substantially horizontal plane, and will be materially above the upper edge of the casing. The record may then be slid in a horizontal direction out of the carrier, without interference in any way by the casing wall. The casing is provided with a cover 25 or top 18, which may be hinged or secured in place in any other suitable manner, and this cover is so designed in respect to the body of the casing that the cover cannot be closed except when the upper side of the drum is substantially horizontal. Thus the cover, when closed, prevents any rotation of the drum.

The carriers are preferably formed as envelopes of tough paper or other suitable fabric or sheet material, and are substantially square, and of such width as to receive the largest size of record. Each envelope has an opening along one edge to permit withdrawal of the record in the direction of the axis of the drum. The upper wall 19 of the envelope has a central aperture 20 which exposes the name, title, or other printed matter at the center of the record, but the aperture is not sufficiently large as to expose any of the matrix grooves of the record. Thus the grooves are protected by the upper wall of the envelope. At the open end of the envelope, the two walls are provided with a recess or notch 21, extending in a sufficient distance so that the edge of the record may be easily grasped and withdrawn from the envelope. To facilitate this removal of the record, the drum may have corresponding recesses in each wall thereof, but preferably the drum is made enough shorter than the envelope so as not to interfere in any way with the grasping of the edge of the record at the recess 21 in the envelope. To prevent any lateral strain on the envelope, or any tendency of the envelope to shift laterally on the drum during the withdrawal of a record, and thus prevent any such displacement of the envelope as would cause them to frictionally engage with the walls of the casing, the drum is

preferably provided with a pair of pins, lugs, or projections 22 on each face thereof, and adapted to extend through corresponding apertures in the several envelopes as they come into engagement with the surface of the drum. These pins or lugs also insure the proper and accurate registry of the several envelopes during the rotation of the drum.

To prevent the drum from turning accidentally, or prevent the weight of the envelopes depending from one side from turning the drum in that direction when one pile is very much higher than the other, I preferably provide friction or resistance means of some kind. As illustrated, the bearing block 23 within which the shaft 17 is mounted, has a split collar portion 24 with a pair of flanges which may be drawn together by a clamping bolt 25, or in any other suitable manner. Within the collar is a split fiber bushing 24^a. Thus the collar may be tightened to offer any desired resistance to the free turning of the drum.

I do not wish to be limited to any specific means for forming the envelopes and connecting them together in series. In fact, all of the envelopes may be made of a single strip of paper folded lengthwise, to form the upper and lower walls, and provided with transverse seams serving as means to divide the space between the opposite walls into separate compartments or envelopes, or individual envelopes might be connected by suitable hinge strips.

As shown in Figs. 7, 8 and 9, each envelope is formed of a separate piece of paper folded to form the two opposite walls, and with the free edges spaced apart to permit the withdrawal of the record. The pieces of paper forming the successive envelopes are not connected together except by means of the strips of tape which perform the double function of hinges and closures for the edges of the envelope. As shown particularly in Fig. 9, two strips of tape 28—28 are connected together by a pair of spaced lines of stitching 29 which extend lengthwise of the tapes and spaced from the free edges thereof. The free edges are separated and the free side edges of the paper envelopes are inserted therebetween and permanently held in place by glue or other securing means. The paper of each two successive envelopes is thus spaced by the fabric strips which form the hinge between the adjacent envelopes. Instead of having the strips of tape extend transversely of the series to form the hinges the strips may extend lengthwise of the series, and each envelope may be a separate and complete one with three edges closed before the connecting of the envelopes together in series. As shown in Fig. 12, a pair of tapes 30 may be employed adjacent to each of the two opposite edges of the en-

velope, each tape extending along one surface of each alternate envelope and along the opposite surface of the intermediate envelopes and the two tapes of each pair 5 being oppositely positioned and closely adjacent to each other. Thus the two tapes, in crossing each other at each edge of each envelope, form a hinge which permits the strip or series of envelopes to freely bend in 10 either direction and permit the envelopes to pile up in zigzag arrangement or order. The drum may be rotated by a suitable handle 31, and the recess or aperture 21 which permits the withdrawal of the record 15 may be at the edge opposite to the handle, so that the handle may be conveniently turned by the right hand and the record withdrawn with the left.

In the form shown in Fig. 1, where two 20 separate casings for records are employed, the separate operating handles for these two casings may be at opposite ends of the construction and in case the tone arm or other part of the phonograph interferes with the 25 withdrawal of the record from the end opposite to the handle the recesses 21 and the open ends of the envelope may be arranged at the same end of the drum as the operating handle.

30 As previously stated, the envelopes are of such size as to receive the largest size of records. I preferably provide means whereby each envelope may receive a smaller size of record and hold it properly centered.

35 This means is illustrated in Figs. 7, 10 and 11 as a pair of strips or cleats 33 of comparatively stiff, tough paper, glued or stitched to the wall of the envelope opposite to the one having the aperture 20, and at 40 the proper spacing. These cleats may lie flat when a large record is inserted, or the free edges may be lifted up to form guides for the edges of the record, if a smaller one be employed.

45 To prevent any undue resistance to the lifting of the envelopes from one pile, or the dropping of them on to the other, the partition 14 is preferably formed of slats, or is otherwise provided with apertures so that 50 air may freely pass through the partition and prevent the formation of an air pocket beneath the envelope. For the same reason the opposite walls of the casing opposite to the partition may have cleats or strips 35

55 acting as guides and permitting the movement of air to or from the space beneath a record carrier during the movement of the latter from or to a pile. To prevent the record carriers from tending to hug the 60 drum as the latter is rotated, the drum itself may be made of skeleton form or provided with air openings 36. The end wall of the casing may be provided with a pair of guides 37 disposed outside of the path of 65 movement of the series of carriers and tend-

ing to prevent the latter from swinging out from the drum in such a way as to interfere with proper stacking, and a similar pair of guides 38 disposed inside of the path of movement of the carriers and preventing 70 the lower edge of a carrier from following the surface of the drum during the rotation of the latter. These last mentioned guides may thus serve as strippers.

To facilitate the location of any particular record, the envelopes are preferably numbered in series from one end to the other, the numbers being sufficiently large and conspicuous so that they may be readily read during a comparatively rapid turning 75 of the drum. Index tabs 39 are also preferably provided for each envelope and bearing a letter or other index of classification. If the records be arranged alphabetically the corresponding initial letter may be attached to each envelope, or if they be classified or arranged according to the general character of the subject, these index tabs 80 may bear such words as "Dance," "Grand 85 opera," etc.

If desired, each end of the series may be permanently connected to the bottom of the casing so that the series will be permanently held in proper position over the drum. In this case the end portions of the series may 90 be made up of dummies or pieces of cardboard, the size of a carrier, as it will not be possible to bring these terminal sections to operative position above the drum for the insertion or removal of records.

Having thus described my invention, what I claim as new and desire to secure by Letters Patent is:—

1. A phonograph record filing cabinet including a casing, a drum, polygonal in cross section and pivoted for rotation therein about a horizontal axis adjacent to the upper end of the casing with the upper side of the drum disposed above the upper edge of the casing wall, and a plurality of record 105 carriers connected together in series and extending over said drum and disposed in two piles below the drum, each carrier being of a width substantially equal to the width of a face of the drum and having an opening in 110 one edge for the lateral withdrawal of the record, whereby upon rotation of the drum any carrier may be brought to a position in a horizontal plane on the upper side of the drum above the casing wall, and the record 115 withdrawn laterally therefrom.

2. A phonograph record filing cabinet including a casing, a drum polygonal in cross section and pivoted for rotation therein about a horizontal axis adjacent to the upper 125 end of the casing, whereby any side of the drum may be brought to a position in a horizontal plane above the upper edge of the casing wall, and a plurality of record carriers connected together in series and extend-

ing over said drum, and disposed in two piles below the drum, each carrier being of a length substantially equal to the length of the casing, and the record being removable from its respective carrier in the general direction of the axis of the drum, and only when the carrier be disposed on the upper side of the drum.

3. A phonograph record filing cabinet including a casing, a drum polygonal in cross section and pivoted for rotation therein about a horizontal axis, adjacent to the upper end of the casing, with the upper side of the drum disposed above the upper edge of the casing wall, and a plurality of record carriers connected together in series and extending over said drum, each carrier being of a width substantially equal to the width of the face of the drum, and of a length substantially equal to the length of the casing, and having an opening in one edge for the lateral withdrawal of the record in a direction parallel to the axis of the drum.

4. A phonograph record filing cabinet including a casing, a drum pivoted for rotation therein about a horizontal axis adjacent to the upper end of the casing with the upper side of the drum disposed above the upper edge of the casing wall, a cover for the top of said casing which when in closed position prevents rotation of the drum and a plurality of record carrying envelopes connected together in series and extending over said drum, each envelope having an opening in one edge thereof for the lateral removal of the record in the general direction of the axis of the drum.

5. A phonograph record filing cabinet including a casing, a drum pivoted for rotation therein about a horizontal axis adjacent to the upper end of the casing with the upper side of the drum disposed above the upper edge of the casing wall, a plurality of record carrying envelopes connected together in series and extending over said drum, each envelope having an opening in one edge thereof for the lateral removal of the record, in the general direction of the axis of the drum and means for preventing lateral movement of the envelope during withdrawal of the record therefrom.

6. A phonograph record filing cabinet including a casing, a drum pivoted for rotation therein about a horizontal axis adjacent to the upper end of the casing with the upper side of the drum disposed above the

upper edge of the casing wall, a plurality of record carrying envelopes connected together in series and extending over said drum, each envelope having an opening in one edge thereof for the lateral removal of the record, and projections carried by said drum and engaging with said envelope for preventing movement of the envelope in the direction of the axis of the drum during the removal of the record.

7. A phonograph record filing cabinet including a casing, a drum pivoted for rotation therein about a horizontal axis adjacent to the upper end of the casing with the upper side of the drum disposed above the upper edge of the casing wall, and a plurality of record carrying envelopes connected together in series and extending over said drum, each envelope having an opening in one edge thereof for the lateral removal of the record, said drum being shorter than said envelope, and said envelope having portions of the opposite walls thereof cut away at the open end, and beyond the end of the drum, whereby the edge of the record may be directly grasped for removal.

8. A phonograph record filing cabinet, including a casing, a drum polygonal in cross section and pivoted for rotation therein about a horizontal axis adjacent to the upper end of the casing, a plurality of record carriers connected together in series, each being of a width substantially equal to the width of a face of the drum, and a cover for said casing adapted to lie closely adjacent to the upper side of the drum and prevent rotation of the latter when the cover is in place.

9. A phonograph record filing cabinet including a casing, a drum pivoted for rotation therein about a substantially horizontal axis, and a plurality of envelopes connected together in series, each carrier having a central aperture exposing the center portion of the record but leaving the matrix grooves covered, and guides within said envelope and secured to one wall thereof at equal distances, upon opposite sides of said aperture for holding records of different size but permitting their removal through the end of the envelope in the direction of the axis of the drum.

Signed at New York, in the county of New York and State of New York, this 14th day of November, A. D. 1921.

CLARENCE NOEL CAHUSAC.
